UNITED STATES PATENT OFFICE.

EDWARD L. BRACY, OF BALTIMORE, MARYLAND, ASSIGNOR TO WRIGHT'S AUTOMATIC TOBACCO PACKING MACHINE COMPANY, OF DURHAM, NORTH CAROLINA, A CORPORATION OF WEST VIRGINIA.

PACKAGING-MACHINE FOR TOBACCO AND LIKE MATERIALS.

1,217,694.

Specification of Letters Patent. Patented Feb. 27, 1917.

Application filed August 30, 1916. Serial No. 117,738.

To all whom it may concern:

Be it known that I, EDWARD L. BRACY, a citizen of the United States, residing at Baltimore, in the State of Maryland, have 5 invented certain new and useful Improvements in Packaging-Machines for Tobacco and like Materials; and I do hereby declare the following to be a full, clear, and exact description of the same, reference being had 10 to the accompanying drawings, forming part of this specification.

This invention relates to a class of machines which has heretofore found its chief field of usefulness in connection with the 15 preparation of small packages of tobacco. Many machines for packaging this class of material are now in common use and the invention is more especially, though not exclusively, applicable to machines known as 20 the Rose tobacco packer, there now being a large number of such machines in use and, generally speaking, such machines conform to the machines illustrated in the United States patents granted to William Rose, 25 Nos. 502,637, dated August 1, 1893, and 586,076, dated July 6, 1897. The invention is illustrated in connection with a machine which is practically identical with that shown in the last mentioned patent, to which 30 patent reference may be had for an understanding of those features of the machine which it is not deemed necessary to illustrate herein for a complete understanding of the present improvements.

35 In the said prior machines a wrapper and a sufficient quantity of tobacco to form each package are fed to an intermittently rotated mold wheel having at its periphery a series of pockets in which the package is given 40 shape and by the movement of the mold wheel each pocket is successively brought into position to first receive the wrapper, then the tobacco; then the side folds of the wrapper are formed, so that the edges over- 45 lap; then the end folds of the wrapper are formed; then the ends of the package are indented; and finally the completed package is discharged from the pocket. The wrappers for the tobacco are usually formed of 50 paper, and sometimes of paper and metal foil, but the paper in most instances is satu-

rated with paraffin or other waxy water-resistant material, and it is the object of the present invention to provide a simple and conveniently applied means whereby the 55 overlapping portions of the side folds and the end folds of the wrapper may be effectually sealed; that is to say, united together in such wise that they are retained in place and the package when completed is practically water tight, or sufficiently so to prevent access of moisture and consequent deterioration of the contents of the package.

In carrying this invention into practice in connection with the Rose tobacco packer provision is made whereby at that stage in the formation of the package where the end folds of the wrapper are being made, the side folds are subjected to the action of a heating element which will sufficiently soften 60 or liquefy the water proofing material of the wrapper to cause the overlapping edges to adhere or unite, and at the next stage in the formation of the package, *i. e.*, that where the ends of the package are usually indented, 65 the side folds are subjected to the action of a cooling element whereby the union of the side folds is completed, and simultaneously, or at that stage in the movement of the mold box, the end folds are subjected to the action 70 of heating elements whereby the water proofing material is softened so that the end folds are caused to unite or adhere together, and at the next stage in the procedure, the said end folds are subjected to the action of a 75 cooling element or elements to complete the sealing operation of the ends. During each of these sealing operations the package itself is clamped firmly in the mold wheel pocket and its shape preserved not only by the walls 80 of the pocket but by a segmental clamping member in which the heating and cooling elements for the side folds are located.

Referring to the accompanying drawings,—

Figure 1 is a partial side elevation with parts in section and parts broken away, of a Rose tobacco packing machine embodying the present improvements, the said view substantially corresponding to Fig. 7 of the 100 Rose Patent No. 586,076.

Fig. 2 is a view looking toward the ma-

chine shown in Fig. 1 from a point of view at the left of Fig. 1 and showing the mold wheel and the movable holding or clamping plate together with the heating and cooling elements.

5 Fig. 3 is a detail section on the line *a—a* of Fig. 2.

Fig. 4 is a perspective view of a partly completed package.

10 Fig. 5 is a section substantially on the lines *b—b*, Figs. 1 and 2.

Fig. 6 is an elevation from a point of view indicated by the line *c—c* in Fig. 1, but omitting the holding or clamping plate.

15 Fig. 7 is a section on the line *d—d*, Fig. 2.

Fig. 8 is a view corresponding to Fig. 6, but with the mold wheel pocket in the next succeeding position where the package is subjected to the influence of the cooling element for the end folds.

20 Like reference characters in the several figures indicate the same parts.

For convenience in understanding the packaging machine, parts illustrated in Fig. 2 which correspond to parts shown in the last mentioned Rose patent are identified by reference numbers corresponding to the reference numbers of the patent. Thus, the number 27 indicates the mold wheel which is

30 intermittently rotated so as to bring the peripheral pockets 42 successively into position for receiving the wrapper and tobacco and for having the folds formed in the wrapper to complete the package. The

35 wrapper having been supplied to a mold, the mold wheel is rotated one step so as to bring the wrapper into position beneath the plunger 96, carried by the oscillatory arm 97, and before the plunger descends a proper quantity of tobacco is discharged from the hopper chute 73 by the reciprocation of the pusher 76, whereupon the plunger 96 descends and compresses the charge of tobacco in the

40 wrapper located in the mold box. The next movement of the mold wheel carries the mold box into position for coöoperating with the side folding devices 104 and 113, mounted on the shaft 105 and these devices in the well known way operate to fold the

45 front and rear edges of the wrapper over the side of the tobacco contained in the box and so as to overlap. The next movement of the mold wheel carries this box having the partly wrapped package therein into position

50 for the formation of the end folds. In moving to this position it passes in behind a segmental clamping or holding plate 173 pivotally mounted on shaft 168, and when the mold wheel comes to rest this segmental

55 clamping or holding plate moves up against the periphery of the mold wheel, thereby clamping the packages contained in three of the mold boxes. The package which has moved from the side folding devices into 60 position for coöperation with the end fold-

ing devices is located immediately opposite a heating element indicated generally by the reference letter F in Fig. 1, and during the time the end folds are being formed by the usual end folding appliances mounted in 70 the frame 145 and having operating arms and connections 154 and 156, and the element 162, the heating element softens the water-proofing material of the wrapper where the side edges overlap, and upon the completion 75 of the end folds the mold wheel makes another movement, bringing the package into a position where, when the clamping or holding plate advances, a cooling element, indicated generally by the reference letter G 80 bears against the overlapped side edges of the wrapper, thereby cooling the softened material, and effectually unites the overlapping edges. In this position the package is brought between two oppositely movable 85 parts which correspond in location and operation to the end punches 169 of the Rose patent, but which parts, in the present invention are in the form of heating elements H shown clearly in Figs. 1 and 2, and while the 90 mold wheel is at rest, these heating elements advance and soften the water-proofing material of the wrapper throughout that part which constitutes the end folds of the package. Conveniently, the heating elements H 95 also serve to indent the ends of the package to a slight degree, thereby insuring a firm pressure and thorough softening of the water-proofing material.

The next movement of the mold wheel 100 brings the package into position between cooling elements I connected with the elements H by arms K so as to move in unison therewith. When the mold wheel comes to rest the cooling elements I advance toward 105 each other and contact with the ends of the package. In this position, as in the other positions, the package is clamped by the holding or clamping plate 173 and the final formation and cooling of the end folds is 110 effected, so that the package is at this stage practically completed and ready for subsequent discharge from the mold wheel. Ordinarily, the feed movements of the mold wheel carry the wrapped and sealed package 115 around, within a segmental guard L to a point where it is desired to discharge the packages from the mold wheel.

With this arrangement it is obvious that 120 a series of packages are being operated upon simultaneously, and during the time that a mold wheel box is receiving a wrapper, another box is receiving a charge of tobacco; another box is in position for the wrapper to have the side folds made; another is in 125 position to have the side folds sealed and the end folds formed; another is in position to have the side folds cooled and the end folds sealed; and another is in position to have the end folds cooled; and during each 130

interval of rest of the mold wheel, one package is in position to be discharged therefrom by suitable means not illustrated herein, as the same forms no part of the present invention.

5 Details of the construction of the heating and cooling elements are illustrated in Figs. 3 and 5 to 8, inclusive. By reference to Fig. 3 it will be seen that the heating element indicated generally by the reference letter F is formed by mounting in a recess of the clamping or holding plate 173 a suitable resistance element M to which electric circuit connections m lead, and this resistance element is partly surrounded by a heat transmitting plate M' which extends to the face of the clamping plate 173 and a surrounding insulation M² for preventing conduction of heat through the plate 173, the whole being held by the liner M³ in which the resistance element and parts M' and M² are mounted. The arrangement is such that the heating element including the parts M to M³ may be readily removed or inserted, and the resistance element itself may be of any known or preferred form or construction. The whole heating element constitutes a flat portion of the face of the clamping plate 173 and the heat is applied throughout a central portion thereof so as to heat the overlapping edges of the side folds of the wrapper, as shown.

35 In Figs. 5, 6 and 7, the cooling element is shown and from these figures it will be observed that there is mounted in the clamping plate 173 a box-like structure N having an internal water circulating passage N' through which cooling water or other medium is circulated from supply pipes N². In these figures there is also shown the end fold heating elements embodying resistance members O having electric circuit connections O' and heat transmitting plungers or plates O², adapted to enter the ends of the mold box and to contact directly with and exert some pressure upon the end folds of the package.

50 In Fig. 8 the end fold cooling elements are illustrated and they embody plungers P having water circulating passages P' therein supplied with water or cooling medium through the flexible pipe connections P². As before stated the end fold heating elements and the end fold cooling elements are connected together by the arms or frames K and move in unison into and out of position to coöperate with the end folds of the packages contained in the mold wheel boxes.

55 In the preferred operation of the machine, the wrappers are formed of paraffin paper, inasmuch as it is found that such paper not only preserves the packages but imparts no objectionable flavor to the contents, and it has the property of readily adhering when overlapping portions are brought together and

subjected to the heating and cooling action hereinbefore described.

Packages which are sealed in the manner referred to are practically impervious to moisture and by sealing the overlapping portions a considerable saving in wrapper material may be effected. Furthermore, the outside dimensions of the package may be reduced without reducing the contents, inasmuch as deep indentations for the ends of the package are unnecessary in order to hold the end folds closed during the subsequent manipulations of the package, such, for example, as its insertion into a metal container or box, as is customary in the art.

What is claimed is:

1. In a package wrapping and sealing machine, the combination with means for intermittently feeding a package of goods and its wrapper into successive positions, and means for making the side and end folds of the wrapper respectively while the package is in different positions, a heater element located in position to subject the overlapping side folds to heat during the formation of the end folds, a cooling element located in position to subject the side folds to a cooling action when the package is in a succeeding position, and heating elements located in position to subject the end folds to heat during the time that the side folds are being cooled.

2. In a package wrapping and sealing machine, the combination with means for intermittently feeding a package of goods and its wrapper into successive positions, of means for simultaneously sealing the side folds and forming the end folds, when the package is in one position, and means for simultaneously cooling the side folds and sealing the end folds when the package is in a succeeding position.

3. In a package wrapping and sealing machine, the combination with means for intermittently feeding a package of goods and its wrapper into successive positions, of means for simultaneously sealing the side folds and forming the end folds of the package when the package is in one position, means for simultaneously cooling the side folds and sealing the end folds, when the package is in a succeeding position, and means for cooling the end folds when the package is in a third position.

4. In a package wrapping and sealing machine, the combination with an intermittently movable mold wheel, having peripheral mold boxes, a curved clamping plate movable toward and from the mold wheel, a heating element carried by said plate in position to coöperate with a package contained in a mold box when in one position, and a cooling element carried by said clamping plate in position to coöperate with the package in said mold box when in a succeed-

ing position, and means for forming side and end folds in the wrapper carried in the mold box.

5. In a package wrapping and sealing machine, the combination with the intermittently movable mold wheel having peripheral mold boxes, a curved clamping plate movable toward and from the mold wheel, and means for forming side and end folds
- 10 of the wrappers carried in the mold boxes, of a heating element carried by the clamping plate in position to coöperate with the wrapper mounted in a mold box in one position, a cooling element carried by the clamping plate in position to coöperate with the wrapper when in a succeeding position, and plungers movable toward and from the ends of the mold boxes, heating elements carried by said plungers for sealing the ends of the package.
- 15
- 20

20 *packing.*

6. In a package wrapping and sealing machine, the combination with the intermittently movable mold wheel having peripheral mold boxes, a curved clamping plate
25 movable toward and from the mold wheel, and means for forming side and end folds of the wrappers carried in the mold boxes, of a heating element carried by the clamping plate in position to coöperate with the
30 wrapper mounted in a mold box in one position, a cooling element carried by the clamping plate in position to coöperate with the wrapper when in a succeeding position, plungers movable toward and from the ends
35 of the mold boxes, heating elements carried by said plungers for sealing the ends of the package, and cooling elements movable in unison with said plungers and positioned to engage the end folds when the package is in
40 a position succeeding that in which the end folds are heated.

7. In a package wrapping and sealing machine, the combination of an intermittently movable mold wheel having peripheral mold boxes, a curved clamping plate 45 movable toward and from the mold wheel, a heating element carried by said plate in position to coöperate with a package contained in a mold box when in one position, a cooling element carried by said clamping 50 plate in position to coöperate with the package in said mold box when in a succeeding position, flexible pipe connections for supplying cooling medium to said cooling element, and means for forming side and end 55 folds in the wrapper carried in the mold box.

8. In a package wrapping and sealing machine, the combination with the intermittently movable mold wheel having peripheral mold boxes, a curved clamping plate movable toward and from the mold wheel, and means for forming side and end folds of the wrappers carried in the mold boxes, of a heating element carried by the clamping plate in position to coöperate with the wrapper mounted in a mold box in one position, a cooling element carried by the clamping plate in a position to coöperate with the wrapper when in a succeeding position, 70 plungers movable toward and from the ends of the mold boxes, heating elements carried by said plungers for sealing the ends of the package, cooling elements movable toward and from the mold boxes and in position to engage the end folds when the package is in a position succeeding that in which the end folds are heated, and flexible pipe connections for supplying a circulating medium to 75 said cooling elements.

EDWARD L. BRACY
